H. L. Lodge Atty.

UNITED STATES PATENT OFFICE.

WILLIAM HERBERT ROLLINS, OF BOSTON, MASSACHUSETTS.

MECHANICAL MUSICAL INSTRUMENT.

SPECIFICATION forming part of Letters Patent No. 621,289, dated March 14, 1899.

Application filed September 2, 1896. Serial No. 604,633. (No model.)

To all whom it may concern:

Be it known that I, WILLIAM HERBERT ROLLINS, a citizen of the United States, residing at Boston, in the county of Suffolk and State 5 of Massachusetts, have invented certain new and useful Improvements in Mechanical Musical Instruments; and I do hereby declare the following to be a full, clear, and exact description of the invention, such as will enable 10 others skilled in the art to which it appertains to make and use the same, reference being had to the accompanying drawings, and to figures of reference marked thereon, which form a part of this specification.

15 This invention relates to mechanical musical instruments employing a perforated traveling sheet to control divers mechanisms by which sound-notes are produced.

20 My improvements relate to the control of the perforated sheet and to mechanism governing the operation of the two drums about which said sheet is alternately wound and un-

25 wound. The object of my invention is to exert tension on the paper sheet when this element is 30 producing sound-notes or when passing from the delivery-roll, and said tension is to be imparted by reverse motion of said delivery-roll. Thus by a positive control of said roll too 35 rapid delivery of the sheet when passing over the tracker-board is prevented.

By means of my improvements the various 40 devices heretofore employed to maintain proper contact of the sheet upon the tracker-board and to produce a drag upon the sheet 35 may be dispensed with.

The drawings herewith presented represent 45 in Figure 1 a front elevation, in part, of a mechanical musical instrument equipped with one form of mechanism embodying my invention and a modification of that in Figs. 2 and 3. Fig. 2 is a side elevation, and Fig. 3 is a front elevation of the arrangement in Fig. 2 and likewise of mechanism for carrying out 50 my invention.

In the said drawings I have shown only so much of a mechanical musical instrument as is sufficient to explain my invention, it being understood that no changes occur in the gen-

eral construction of the instrument, and, furthermore, that my improvements may be applied to any form or type of apparatus in which a perforated traveling music-sheet is employed.

In the present instance I have shown in 55 Figs. 1 and 3 the case at 2, the delivery-roll at 3, the receiving-roll at 4, and the paper sheet at 5. This latter co-operates with the tracker-board 6, perforated with apertures, which receive air passing therethrough to the air- 60 valves.

In the present mode of operation reference is had more especially to Fig. 3, where the receiving-roll 4 or that about which the perforated sheet is wound during the performance 65 of a sheet of music is positively controlled by a gear or toothed wheel 7, operated by a pinion 8, adjustably affixed upon a shaft 9 to some prime motor such as is usually employed in instruments of this class.

70 Heretofore various devices have been in service to press the sheet upon the tracker-board and thus serve as a drag; but so far as my knowledge goes nothing has ever before been employed to control the unwinding of 75 the sheet from the delivery-roll itself by imparting to said roll a positive rotation in a direction reverse to the direction of rotation of the receiving-roll and causing an intermission or suspension of such rotation of the delivery- 80 roll when a certain degree of tension is produced in the note-sheet. By my arrangement I avoid the use of all intermediary mechanism heretofore made use of between the delivery and receiving rolls and at the same 85 time control positively the rotation of the said delivery-roll. In this way I secure two important results—first, the retention of the sheet in a most efficient manner upon the tracker-board, and, secondly, I obviate any 90 excess in the rate of rotation of the delivery-roll whereby the music-sheet is unwound faster than it is wound upon the receiving-roll.

To carry out my improvements and yet 95 adapt my invention to the usual form of construction under instruments of this class, I mount a drum or grooved wheel 12 loosely

upon the shaft 9 of the receiving-roll, while a secondary wheel 13 is made fast to the shaft of the delivery-roll. A spring 14, the tension of which is readily controlled, is made fast 5 to the shaft 9 and bears against the wheel 12, while a flexible band 15 interconnects the two wheels. Thus it is evident that rotation of the shaft to cause the sheet to be coiled about the receiving-roll occasions reverse rotation of the delivery-roll, which is positively controlled by the belt, together with the co-operating wheels 12 13 and the spring 14. As before stated, this element can be regulated 10 to vary the difference in the rate of revolution between the two rolls.

In the operation of the music-sheet and in order to carry out my invention a certain degree of tension is to be exerted upon the music-sheet as it is unwound from the delivery-roll, and this tension is produced, preferably, by allowing the wheels 12 or 13, as the case may be, to slip under the pressure of the friction device. It is evident that the drag upon the sheet is controlled and regulated by the 20 spring-tension and that both rolls are simultaneously operated and positively regulated in their movements both during the unwinding or the rewinding of said music-sheet.

In order to return the sheet to the delivery-roll after the performance of a piece of music, a clutch 16, fast upon the shaft 9, but mounted for sliding movement and operated by a lever 19, is fitted with rods or pins 17, which engage in the wheel 12. This clutch 30 is interconnected with the pinion 8 by means of a sleeve. Hence engagement of the clutch with the wheel 12 interconnects the latter positively with the shaft 9, while the roll 4 is released. Continuous movement of the shaft 35 now reverses the movement of the sheet and causes it to return to the delivery-roll 3 in readiness for a repetition of the piece, if it is so desired, or for removal if a different piece is to be performed.

In Fig. 1 it will be seen that the wheel 12' 45 is fast upon the shaft 9, while the wheel 13' is frictionally secured to the shaft of the delivery-roll by an adjustable spring 14'. This frictional engagement particularly described 50 comprises a sleeve-shaft 20, on which is made fast the wheel 13', while the spring 14' is affixed to said sleeve 20 and bears with its free end on the delivery-roll shaft. A cross-belt 15 serves to impart a reverse rotation of said roll with respect to the receiving-roll. The tension of the spring 14' is easily adjusted by means of the screw 18, located in the free end thereof, the opposite fixed end being made fast to the sleeve of the wheel 13'. This latter 55 arrangement is a slight modification of that shown in Figs. 2 and 3; but either a direct or a cross belt I consider embodies my invention, which consists in the means claimed for the control of the delivery-roll from the main shaft 60 of the instrument, so as to produce a retarda-

tion of said delivery-roll and cause a drag upon the note-sheet.

What I claim is—

1. In a mechanical musical instrument, the combination with a delivery-roll, of a receiving-roll, means for driving said receiving-roll, connections between said receiving-roll and said delivery-roll to impart a positive rotation to the latter in a direction reverse to that of the receiving-roll and thus produce a drag 70 upon the note-sheet, and means for intermitting the reverse rotation of said delivery-roll and permitting it to rotate in the same direction as the receiving-roll when the drag on the note-sheet produces a certain degree of tension.

2. In a mechanical musical instrument, the combination with a receiving-roll, of means for rotating said roll, a delivery-roll, means for positively rotating said delivery-roll in a 85 direction reverse to the direction of the receiving-roll to produce a drag upon the note-sheet, and means for causing intermission of the reverse rotation of said delivery-roll and permitting forward rotation thereof when a 90 predetermined tension or drag has been produced on the note-sheet.

3. In a mechanical musical instrument the combination with a music-sheet, a tracker-board, and delivery and receiving rolls, of 95 apparatus arranged to impart simultaneous rotation to said rolls, and drag mechanism adapted to create resistance to the rotation of the delivery-roll and thereby produce tension upon the music-sheet, as specified.

4. The combination with a delivery-roll, a receiving-roll, and a music-sheet adapted to be coiled and uncoiled about said rolls, of a tracker-board, a driving-shaft for the receiving-roll, a wheel affixed to the shaft of the delivery-roll, a loose wheel upon the driving-shaft, a flexible band to connect the two wheels, and a friction device, as a spring, to produce retardation of the delivery-roll, substantially as described.

5. In combination with a tracker-board, a traveling music-sheet, a receiving-roll, an actuating-shaft, interconnecting gears to impart rotation to said receiving-roll, and a loose wheel frictionally connected with said shaft, of a delivery-roll, its supporting-shaft, a wheel fast thereon, a band to connect the fast and loose wheels, and a clutch to engage the loose wheel, whereby the actuating-shaft and the delivery-roll are positively interconnected for rewinding of the sheet about the said delivery-roll, substantially as set forth and explained.

In testimony whereof I affix my signature in presence of two witnesses.

WILLIAM HERBERT ROLLINS.
